UNITED STATES PATENT OFFICE

EDWARD KARFIOL, OF NEW YORK, N. Y.

DESIGN FOR A DOILY

Application filed February 17, 1933. Serial No. 47,242. Term of patent 14 years.

To all whom it may concern:

Be it known that I, EDWARD KARFIOL, a citizen of the United States, residing in New York, in the county of New York and State of New York, have invented a new, original, and ornamental Design for Doily, of which the following is a specification, reference being made to the accompanying drawing, forming part thereof, in which:

The figure represents a face view of a doily showing my new design. The full lines of the drawing show one-quarter of the design in detail, the other three-quarter sections indicated in dotted lines except the border which is shown in full lines, being repetitions of the detailed illustration arranged in proper relation thereto. The centre motif is shown in full lines except a portion of the border which is a repetition of the full lines.

I claim:

The ornamental design for a doily as shown and described.

EDWARD KARFIOL.
